UNITED STATES PATENT OFFICE.

CYRUS W. BOLSINGER, OF MUNHALL, PENNSYLVANIA.

LIFTING-TONGS.

SPECIFICATION forming part of Letters Patent No. 542,985, dated July 23, 1895.

Application filed May 8, 1895. Serial No. 548,476. (No model.)

To all whom it may concern:

Be it known that I, CYRUS W. BOLSINGER, of Munhall, in the county of Allegheny and State of Pennsylvania, have invented a new and useful Improvement in Lifting-Tongs, of which the following is a full, clear, and exact description, reference being had to the accompanying drawings, forming part of this specification, in which—

10 Figure 1 is a side elevation, partly in section, showing my improved tongs applied to an armor-plate; and Fig. 2 is an end elevation of the same.

15 My invention relates to the tongs employed for lifting and transferring metal or other heavy bodies, and is designed to afford a device of this character which can be readily adapted to different thicknesses of plate and will give a firm and secure hold thereon.

20 To that end it consists in a central fulcrum-plate having movable gripping-pins therein and levers provided with cam-faces arranged to force the pins against the plate or other body and grip it firmly between them. It 25 also consists in the construction and arrangement of the parts as hereinafter more fully described, and set forth in the claims.

In the drawings, in which similar numerals indicate corresponding parts, the fulcrum-plate 2 consists of two plates 3 and 4, secured to a central spacing-plate 5 by through bolts or rivets 6. The plates 3 and 4 are provided with a lower central recess, and the spacing-plate is provided with two depending legs 7 and 8 on opposite sides of the recess which receives the plate. Within the legs of the spacing-plate are arranged the oppositely-movable gripping-pins 9, which are preferably provided with serrated surfaces to engage the body to be lifted. Two levers 10 and 11 are pivotally supported in the plates 3 and 4, and are provided with cam-faces which engage the outer ends of the gripping-pins and force them inwardly when a lifting force 40 is imparted to the upper ends of the levers by means of the chains 12. The chains are

connected to a trolley on a jib of a crane, or to any other lifting element, and it is obvious that when the jib is raised the levers, being swung inwardly, drive the pins inwardly 50 against the plate with a force proportionate to its weight. To hold the levers in retracted position when the tongs are lowered upon the article, I provide holes 13 in the levers, through which bars or rods may be thrust, which, 55 abutting against the ends of the plates 3 and 4, prevent the inward swinging of the levers.

The advantages of my invention will be apparent to those skilled in the art, since the pins 9, which rest loosely in their holes, may be 60 easily removed and replaced by longer or shorter ones to correspond to the thickness of the plate to be lifted. Moreover, when their surfaces become worn they are easily taken out and dressed and retempered. 65

Many changes may be made in the form and arrangement of the parts without departing from my invention, since

What I claim is—

1. Lifting tongs comprising a central fulcrum plate, slideable gripping-pins mounted therein, and levers having cam-faces arranged to contact with said pins; substantially as described. 70

2. Lifting tongs comprising a central fulcrum plate, having a recess to receive the body to be lifted and provided with holes on opposite sides of said recess, pins loosely mounted in said holes, and levers arranged to force said pins inwardly; substantially as described. 75

3. Lifting tongs comprising a central fulcrum plate, slideable pins mounted therein, levers arranged to contact with said pins, and means for preventing the inward movement 80 of the levers; substantially as described. 85

In testimony whereof I have hereunto set my hand.

CYRUS W. BOLSINGER.
